UNITED STATES PATENT OFFICE.

WILLIAM SOMERS, OF SOUTH NORWALK, CONNECTICUT.

COMBINED DETACHABLE CORSET AND BRASSIÈRE.

Application filed December 5, 1925, Serial No. 73,299. Renewed June 28, 1927.

The invention relates to corsets, and to combined detachable corsets and brassières. An object of the invention is to provide improved means for detachably connecting 5 a corset and its brassière. The connection between these garments utilizes the bones of the corset in a manner which will be more particularly described hereinafter. A further object is to enable the bones to be 10 readily removable from the corset.

In the accompanying drawings forming a part hereof:

Fig. 1 is a front elevation of the combination garment with the front corner portion 15 of the corset or girdle turned down to show parts behind;

Fig. 2 is a sectional elevation of the combination garment, looking at the inside of the back, with a portion of the brassière 20 broken away;

Fig. 3 is a front view of the brassière;

Fig. 4 is a rear view of the brassière;

Fig. 5 is a sectional elevation of the corset or girdle, looking at the inside of the front; 25

Fig. 6 is a horizontal section through the front portion of the corset or girdle, taken on the line 6—6 of Fig. 5;

Fig. 7 is a vertical section through the rear portion of the combination garment on 30 the line 7—7 of Fig. 2; and

Fig. 8 is a sectional perspective view taken on the same line, illustrating the relations when slipping the stiffeners in or out of the top pockets.

The corset 2 illustrated in the foregoing 35 views is of the girdle or step-in type. It may be provided at one of the upper side regions with a vent 3, closed by hooks and eyes. Such girdles are composed of elastic and inelastic sections, the drawing illustrating 40 a front inelastic section 4 of strong material, a rear section 5 of similar material, and two elastic side sections 6 of elastic webbing. The front section may have an elastic gusset 7 at the bottom.

The brassière 8 is made of one of the materials usual for such garments, is provided with shoulder straps 9, and is shown as opening down one side front region at 10, 50 the opening being closed by customary fastenings 11.

Sewed across the outside of the front lower portion of the brassière is a strip 12. This strip is sewed to the fabric of the 55 brassière by stitching 13 around the edges

of the strip and by two pairs of transverse rows of stitching 14. The stitching 13 is omitted between the rows of stitching 14, so that the result is to provide a pair of keeper openings 15 between the keeper-strip 60 and the wall of the brassière. A similar, longer keeper-strip 12^a is sewed to the outside of the lower back portion of the brassière by stitching 13^a, 14^a, so as to form three keeper openings 15^a. The keeper openings 65 15 at the front are preferably somewhat divergently inclined, as shown.

On the inside of the front section of the corset there is a lining-piece 16, which is secured to the body wall at the sides and 70 bottom but is free at its upper edge 17 and for a considerable distance downward from said edge, so that this lining-piece can be drawn away from the body wall by inserting a finger behind the lining-piece. This 75 lining-piece is provided with two deep divergently-inclined stiffener pockets 18, which are open at their upper ends and are closed at their lower ends by stitching 19. The upper edge of the lining-piece 16, and 80 therefore the upper ends of the pockets 18, are below the top of the corset. Another, narrower lining-piece 20 is sewed inside the upper portion of this section of the corset, and is formed with two short top pockets 85 21, which are in alignment with the pockets 18 and are open at the bottom. Between the upper and lower, or top and main, pockets 21 and 18 thus formed, there is a separation corresponding approximately to 90 the width of the keeper-strip 12 on the brassière. A bone or stiffener 22 is inserted 95 removably in each of the pockets 18, wherein the major portions of these stiffeners are enclosed. The upper portion of each stiffener extends across the space between the top of the pocket 18 and the bottom of the corresponding pocket 21, and its upper end is received removably in the latter pocket. Since the lining-piece 16 carrying the main 100 pockets 18 is substantially free from the outer wall of the corset, it is easy to slip the upper ends of the bones into and out of the top pockets 21.

In order to connect the garments, the upper portions of the bones are passed through the keeper openings 15 on the front of the brassière, and are then caught in the top pockets. Conversely, to disconnect the garments, the upper ends of the bones are 110

slipped out of the top pockets, whereupon the keeper on the brassière will slip off the bones.

The construction at the back of the corset is of a similar nature. The partially free lining-piece 16^a carries three main stiffener pockets 18^a, and the upper lining-piece 20^a is formed with three top pockets 21^a. The relation between these parts is the same as 10 the relation between the similar parts inside the front section of the corset. The upper portions of the bones 22^a pass through the keeper openings 15^a on the back of the brassière and into the top pockets 21^a, into and 15 out of which the upper ends of the bones can easily be slipped. The bones are entirely removable from their pockets, and consequently the corset as well as the brassière can be washed when the garments are taken apart.

20 Various changes in the details may be made without departing from essentials. The keepers on the brassière may be formed in other specific ways. While it is advantageous to form the two keepers on the front 25 of the brassière in one strip, such as 12, or between said strip and the wall of the brassière, it will be manifest that separate keepers might be sewed to the garment at the proper points, and the same applies to the 30 rear keepers. The function of the keepers is to provide openings through which the bones pass between the pockets 18 or 18^a and 21 or 21^a, and to lie between these intermediate portions of the bones and the wall of 35 the corset, so that as long as the upper ends of the bones are caught in the top pockets the brassière will be held firmly to the corset and will not move out of place. The loose lining pieces or flaps 16, 16^a constitute flexible connections between the pockets 18 and 18^a and the body of the corset, permitting these pockets to be drawn inward away from the corset wall in order that the upper ends of the 40 bones may be slipped into and out of the short pockets without difficulty.

45 It will be apparent that a construction such as described, permitting the ready removal of the bones, is likewise desirable in a corset which may be worn without a brassière.

What I claim as new is:

1. A combination detachable corset and brassière, the corset being provided with stiffeners and pockets, said pockets comprising 55 upper pockets and lower pockets with a separation between, the brassière being provided with keepers through which said stiffeners are passed, said keepers being retained on the portions of the stiffeners between said upper and lower pockets to connect the garments together, and being free to slip off the stiffeners when the ends thereof are slipped out of the upper pockets on the corset.

15 2. A combination detachable corset and

brassière, the corset being provided with stiffeners and pockets, said pockets comprising upper pockets and lower pockets with a separation between, the brassière being provided with keepers through which said stiffeners are passed, said keepers being retained on the portions of the stiffeners between said upper and lower pockets to connect the garments together, and being free to slip off the stiffeners when the ends thereof are slipped out of the upper pockets on the corset, said stiffeners being entirely removable from the pockets.

3. In a combination detachable corset and brassière, means of connection between the garments comprising a plurality of stiffeners, main pockets on the corset receiving the major portions of said stiffeners, top pockets on the upper portion of the corset to receive the upper ends of the same stiffeners, and keepers on the brassière which are retained by the stiffeners passing through them between said main and top pockets, the garments being disconnectible by slipping the upper ends of the stiffeners out of the top pockets.

4. In a combination detachable corset and brassière, means of connection between the garments comprising a plurality of stiffeners, main pockets on the corset receiving the major portions of said stiffeners, top pockets on the upper portion of the corset to receive the upper ends of the same stiffeners, means connecting said main pockets to the corset so that said pockets may be drawn inward away from the corset wall to which the top pockets are secured, and keepers on the brassière which are retained by the stiffeners passing through them between said main and top pockets, the garments being disconnectible by slipping the upper ends of the stiffeners out of the top pockets.

5. In a combination detachable corset and brassière, the combination of a lining-piece in the corset, said lining piece being free at the top so that it may be drawn away from the corset wall, the top of said lining-piece being below the top of the corset, a plurality of stiffener pockets carried by said lining piece, corresponding top pockets on the corset, stiffeners in and extending above said lining-piece pockets so that their upper ends may be slipped into and out of said top pockets, and keepers on the lower part of the brassière through which said stiffeners are passed to detachably connect the garments.

6. The combination of a corset having front and rear lining-pieces, said lining-pieces being free at the top so that they may be drawn away from the corset wall, the tops of said lining-pieces being below the top of the corset, sets of stiffener pockets carried by said lining-pieces, corresponding top pockets on the corset, stiffeners in and extending above said lining-piece pockets so

that their upper ends may be slipped into and out of said top pockets, and a brassière having keepers on the lower part thereof through which said stiffeners are passed to

5 detachably connect the garments.

7. In a corset, a lining-piece on the inside of the corset wall, said lining-piece being secured to the corset wall at regions widely spaced apart laterally and between said

10 regions being free at its top and for a considerable distance downward so that it may be drawn away from the corset wall, the top of said lining-piece being below the top of the corset, a plurality of spaced stiffener

15 pockets carried by said lining-piece, corresponding top pockets on the corset, and a set of stiffeners removably mounted in the lining-piece pockets and adapted to have their upper ends slipped into and out of said top

20 pockets.

8. In a removable boning for corsets, a

deep main stiffener pocket on the corset, a stiffener removably seated in said pocket with its end extending therefrom, a short pocket on the corset into and out of which

25

said end is to be slipped, and a flexible connection between said main pocket and the corset enabling said pocket to be drawn freely away from the corset wall to permit ready insertion and removal of the stiffener.

30

9. In a removable boning for corsets, a deep main stiffener pocket on the corset, a stiffener removably seated in said pocket with its end extending therefrom, a short pocket on the corset into and out of which

35

said end is to be slipped, and a free lining piece carrying said main pocket so that said pocket may be drawn freely away from the corset wall to permit ready insertion and removal of the stiffener.

WILLIAM SOMERS.
